UNITED STATES PATENT OFFICE

GEORGE A. WILLIAMS, OF DECATUR, ILLINOIS, ASSIGNOR TO WILLIAMS SEALING CORPORATION, OF DECATUR, ILLINOIS, A CORPORATION OF ILLINOIS

MEANS FOR SEALING CLOSURES

Application filed January 4, 1928. Serial No. 244,402.

This invention relates to a novel means for sealing closures upon containers. Containers as a rule are of glass or other vitreous material and are provided with a neck upon which a closure is placed. Closures as a rule are of metal and usually provided with a liner which liner may be, and usually is, compressible to a certain extent for the purpose of making a tight joint or seal between the closure and the neck of the container.

Some closures are threaded upon the neck or spout of the container while others are crimped and still others secured by means of some contractible means carried by the closure itself. For numerous liquids carried in containers, an ordinary seal of the closure obtained by a slight compression of the liner is sufficient whereas in others, such as oil, it is imperative to have a very tight seal obtained by a greater unit of compression of the liner between the closure and neck of the container in order to prevent seepage due to capillary attraction and other causes. The liners of the closures now in common use are of cork or some composition and in most closures are compressible to at least a certain degree and in some of them to a very high degree. Pressure is of course necessary to effect this compression and this compression is applied either directly to the closure downwardly upon the container or upwardly to the container toward the closure or in both directions. In all instances so far as I am aware the pressure is communicated to the entire container. In some instances where the container is very thick and strong, this is not particularly objectionable but in other classes of containers such as bottles, the body thereof is as a rule weaker than the neck thereof and consequently if pressure be applied there is loss due to breaking the container.

Commercial practice has demonstrated that glass bottles are frequently broken in attempting to apply sufficient pressure in the application of the closure to effect a tight seal by compression of the liner.

The object of my invention therefore is to provide a means whereby a perfectly tight seal can be obtained without subjecting the

container as a whole to any pressure whatsoever and this I accomplish by applying all of the pressure to the neck of the container and to the outer end thereof which portions are as a rule strongest part of the container due to increased thickness of the walls thereof and to the vertical liner thereof. It will be understood that by supporting the container by the neck thereof the pressure will be received by the supported neck portion and the supporting means.

Heretofore from 150 to 200 pounds sealing pressure has been considered a very high pressure to apply to the compression of the liner. This pressure, however, in numerous instances is not sufficient to effect a tight seal for certain liquids. By means of my novel method and means, I am able to obtain a sealing pressure of from 300 to 400 pounds or more effecting a denser compression ring in the liner thereby making a perfectly tight seal for all liquids.

Broadly speaking, therefore, my method consists in supporting the container at the upper portion of the neck thereof, applying the closure thereto and pressing the same into sealing contact with the end of said neck, said neck only of the container receiving the pressure and leaving the body portion of said container unaffected by said pressure.

My invention also includes the means for supporting the container in the manner above described and applying the closure thereto with a sealing pressure. The invention consists also in certain details hereinafter fully described and set forth in the appended claims.

It will be understood that the broad idea of my invention is applicable to various forms of apparatus and it is immaterial whether the closure is screwed on, crimped on or fastened in any other manner so long as the container is supported by that portion of the neck capable of withstanding the direct pressure necessary to effect the sealing operation. Consequently, I have only illustrated one form of apparatus for carrying out my invention.

In the drawings, Fig. 1 is a side view of

this one form of apparatus for carrying out my novel method; Fig. 2 is a face view of the same; Fig. 3 is a detail sectional plan view showing the gripping jaws and Fig. 4 is an enlarged view of the neck of the container and a cap applied thereto, and the direct supporting means for said container.

Referring to the drawing, 10 indicates the container and 11 the neck thereof, the outer end 12 being somewhat thicker than the neck proper. This is the usual practice as all necks are rounded, flanged or thickened in some manner. In the present instance, I prefer to also form the exterior of the neck with a re-entrant annular groove 13 and an annular rib or enlarged portion 14 directly beneath the groove 13 and this annular enlarged portion 14 preferably terminates in a shoulder 16 between the lower end thereof and the exterior of the neck proper. This shoulder is and may be very small although if for any reason it is desirable it may be made somewhat larger. The closure 17 has a liner 18 of cork or any other suitable material and in the application of the closure the liner 18 is brought into contact with the extreme end of the neck of the container.

As previously stated, the closure may be of the screw type or crimped type or it may be of a type in which the fastening means is carried by the cap itself, such as the clamping ring 19 and lever 20, shown in Fig. 4 of the drawing.

For the purpose of supporting the container by the neck, I employ any suitable supporting means and as one form, I have shown two clamping jaws 21 notched at 22 to receive the neck of the bottle therebetween. These jaws are pivoted at 23 upon a bracket 24 which in turn is adjustably fastened to a standard 25. The opposite ends of the jaws 21 are notched or cut away upon their contiguous faces, as indicated at 26 and between these ends there reciprocates a wedge shaped plunger 27 for the purpose of bringing the outer ends of the jaws together for the purpose of gripping the neck of the shoulder and a spring 28 may be arranged between the said jaws for the purpose of spreading the outer ends when the wedge shaped plunger is withdrawn or moved upwardly.

This wedge shaped plunger may be carried by an arm 29 adjustably secured to a rod 30, the upper end of this rod being loosely connected to a lever 31 fixed on a shaft 33 and actuated by a rod 32 or any other suitable actuating mechanism. The standard 25 is carried horizontally outwardly as shown at 25^a and formed with a housing 25^b in which is journaled a shaft 33 carrying an arm 34, the inner end of this arm being reduced and working in a recess 35 in the forward face of a vertically sliding block 36 and through which passes the vertical rod 37 carrying

upon its lower end a cap chuck 38, the lever tripping finger 39 and lever 40 and shaft 41 for actuating said tripping finger. The rod 37 is secured in the block 36 by means of a set screw 42 and this block is preferably provided with an integral collar 36^a which acts as a stop to limit the downward movement of the block.

From the foregoing, it will be understood that the neck of the container is inserted between the jaws 21 and then by the application of pressure upon the rod 32, the lever 31 is caused to move downwardly, carrying with it the rod 30 which, through the medium of the bracket arm 29, forces the wedge shaped plunger 27 between the ends 26 of the jaws 21 causing the forward ends of the jaws 21 to move inwardly and grip the neck of the container, and the notches or recesses 22 are of such shape as to snugly grip the neck of the container without undue pressure.

In practice, I prefer to have the neck of the container enlarged as shown at 14 and terminating in a slight shoulder 16 at the lower end thereof so as to provide a convenient seat between the neck of the container and the gripping jaws.

At the same time that the lever 31 is moving the rod 30 downwardly, it is also rocking the shaft 33 and arm 34. This arm 34 engaging as it does the block 36, forces said block downwardly, carrying with it the rod 37 provided with the cap carrying chuck 38 at its lower end. The cap 17 carried by the chuck is forced upon the end of the neck of the container and the continued pressure upon the rod 32 causes the closure to be forced down tightly upon the neck of the container compressing the liner and effecting a tight seal.

The lever tripping mechanism can then be actuated or, in case the chuck is provided with a crimping or screwing mechanism, these operations can be taking place at the same time, the paramount factor being the supporting of the container by the neck at the reinforced or strengthened portion thereof so that the entire sealing pressure is applied to only that portion of the container neck capable of withstanding the same and completely relieving the container as a whole from any such excessive pressure.

It will thus be seen that I provide a novel method of effective perfectly tight seals without endangering the container proper and also a suitable means for carrying out such method.

Having thus described my invention, what I claim is:—

1. In a device of the kind described, the combination with a pair of gripping jaws adapted to grip and support a bottle, in a vertical position, of a vertically movable actuating plunger for holding said jaws in engagement with the bottle, a vertically movable

chuck for closures, a pivoted shaft, a lever fixed on said shaft having a sliding connection with said plunger, a sliding block having a recess, an arm fixed on said shaft having a rounded portion extending into said recess, a rod having a connection with said chuck, means for adjustably securing said rod to said block and means for actuating said lever.

2. In a device of the kind described, the combination with a pair of gripping jaws and means for supporting the same in a horizontal position, a vertically movable actuating plunger for moving said jaws towards each other to grip a bottle neck and support the same in a vertical position, a sliding block, a rod fixed in said block carrying a chuck for closures, means for limiting the sliding movement of said block, said block having a recess, a pivoted shaft, an arm fixed on said shaft having a reduced portion extending into the recess of said block for positively reciprocating said chuck, a lever fixed on said shaft having a loose connection with said plunger for positively reciprocating said plunger, and means for actuating said lever to positively cause said chuck and plunger to move downwardly in unison.

In testimony whereof, I hereunto affix my signature.

30 GEORGE A. WILLIAMS.
